UNITED STATES PATENT OFFICE.

JULIUS A. FLESCH, OF CHICAGO, ILLINOIS.

DESIGN FOR A SALES BIN OR BOX.

SPECIFICATION forming part of Design No. 25,199, dated February 25, 1896.

Application filed August 19, 1895. Serial No. 559,851. Term of patent 7 years.

To all whom it may concern:

Be it known that I, JULIUS A. FLESCH, a citizen of the United States, residing at Chicago, in the county of Cook and State of Illinois, have invented and produced a new, useful, and original Shape or Design for Sales Bins or Boxes, of which the following is a full, clear, and exact specification, reference being had to the accompanying drawing, forming a part thereof, and which illustrates a sales bin or box embodying my design in perspective.

The leading feature of my design consists of the sales bin or box having the inclined front end A, through which appears an inclined wall or partition B, which apparently constitutes the inner wall of a comparatively shallow upright inclined compartment.

The front inclined end of the box or bin is provided with a surrounding border composed of two beads α apparently constituting a rectangular opening in which is situated a plate

C, which is inclined in the plane of the inclined end of the box and through which the wall or plate B appears. ²⁵

The front end of the box, for a short distance below the lower one of the horizontal beads α , is substantially upright or vertical, as shown at A'.

The top of the box or bin is provided near the front end with a depression or countersink D, and the rear end of the box is inclined downwardly, as shown at E, to a vertical portion F, which constitutes its extreme rear end. ³⁰

Having thus described my invention, what I claim as new therein, and desire to secure by Letters Patent, is— ³⁵

The new, useful and original shape or design for a sales bin or box substantially as herein shown and described.

JULIUS A. FLESCH.
